CARRIER

Paul J. Niemack, Denver, Colo., assignor to Remington Arms Company, Inc., Bridgeport, Conn., a corporation of Delaware

Application July 12, 1943, Serial No. 494,399

6 Claims.

(Cl. 206—3)

This invention relates to a device for the handling and temporary storage of an orderly arrangement of a plurality of small articles such as ammunition primers.

The common cartridge primer comprises a metallic cup having a height of the order of one-and-one-half times its diameter. While there is substantial variation in size for different cartridges, the diameter of the primer cup of a common cartridge is of the order of .2". Within the primer cup is placed a percussion sensitive priming mixture, and above the mixture a metallic anvil having a point which is partially embedded in the priming mixture and a base which is brought to a position substantially flush with the mouth of the cup. In manufacture, the priming composition is first placed in the cups and the cups are arranged in apertures in a suitable plate, the anvils superposed thereon and pressed into place in an anvil or primer assembly press. The primers thus assembled must all subsequently be visually inspected on both sides for metal defects, presence of priming mixture, proper location and seating of anvil, etc. Thereafter, a check sample inspection may be required. After all inspection operations, the primers are dried in a heated chamber and subsequently fed in orderly arrangement to a machine which inserts them into cartridge shells.

In the past, it has been customary to dump primers as delivered from the primer assembly machine into an appropriate receptacle, later rearrange them in place for the purpose of inspection, again dump them into a receptacle for transfer to the drying room and subsequently to the cartridge shell priming machine, and there again arrange them in orderly fashion right side up for feed to such machine.

The present invention comprises a tray receptacle or package adapted to receive a lot of assembled primers directly from the primer assembly machine, all the same side up, and to maintain such an orderly arrangement throughout the operations of inspection, moving, drying, additional moving and delivery to the shell priming machine. The receptacle is so constructed as to enable complete visual inspection of all parts of the assembled primers and to permit removal of any defectives without upsetting other primers in the receptacle.

In the drawings:

Fig. 1 is a perspective of the appliance of the present invention, so opened as to show in a single view the relationship of all of the parts thereof. It should be noted that this position is an abnormal one which will not be assumed by the receptacle in ordinary use.

Fig. 2 is a perspective of the device, opened in position to receive a transfer plate bearing a lot of primers as delivered by the primer assembly machine.

Fig. 3 is a perspective of the device inverted from the Fig. 2 position to permit the removal of the transfer plate; this position also enabling inspection of one side of the primers.

Fig. 4 is a perspective of the device, opened to permit inspection of the side of the primers opposite that which is enabled by the device in the Fig. 3 position.

Fig. 5 is a perspective of the device, closed and in condition for transportation.

Figs. 6 and 7 show in two positions one of the primers to be handled by the device.

While any suitable material may be used, an appropriately hard fiber board is preferred.

15 The device comprises a flat base 10 having located adjacent the longitudinal margins thereof shallow upstanding ribs 11, these ribs being of sufficient height to obstruct lateral displacement of the articles to be placed in the device but of a height substantially less than the height of such articles. To one end of the base 10 there is hinged, preferably by a cloth hinge 12, a frame or mask identified generally by the numeral 13 comprising continuous end members 14 (one of which receives the cloth hinge 12), a continuous back member 15, and partial front members 16 joined to or integral with the end members 14 but spaced from each other. The gap between members 16 may provide clearance for the handle portion of 20 a transfer plate on which articles such as primers are placed in the device, as well as serving other purposes which will hereinafter appear. To the back member 15 of frame 13 is hinged, preferably by a cloth hinge 17, a cover 18. To the 25 mid-portion of the free edge of cover 18 is hinged preferably by a cloth hinge 19, a filler block 20 adapted, when cover 18 is closed against frame 13, to fill the space between the frame members 16, thus completing a rectangular frame but enabling 30 the member 20 to be turned on its hinge to facilitate the removal of articles contained within the frame 13 and supported on the cover 18.

In the handling of primers, the device is used as follows:

45 The base 10 being down, the device is placed on a suitable table or other support and opened as shown in Fig. 2, the frame 13 and cover 18 pivoting about the hinge 12. A lot of primers, as assembled in the primer assembly machine and supported on a suitable transfer plate, are placed upon the base 10. The cover 18 and frame 13 are then closed over the primers and transfer plate, after which the device is inverted, the cover 18 being placed upon the table or other support. 50 The base 10, which is now on top and thus functions as a cover, is rotated about hinge 12 to expose the primers now supported on cover 18 within frame 13 and the transfer plate which supported the primers when they were placed in the device but now lies on top of them. The transfer plate is thereupon removed. Inspection of 55 60

one side of the primers may take place at this point, or the base 10 may be again moved about its hinge to close, as illustrated in Fig. 5, to permit transportation to the inspectors. At inspection, the base 10 being up, the device is opened, again in the manner illustrated in Fig. 3, and one side of the primers inspected. If defectives are found, the filler block 20 is turned about its hinge to enable the defectives to be removed by sliding off from their support 18, rather than being picked up with the fingers with the danger of inverting other primers. When the inspection of the one side of the primers is complete, the device is closed, as above described, inverted, and cover 18 is opened by rotation about hinge 17; the frame 13 remaining in juxtaposition to the base 10, defective articles are again removed by sliding through the gap between the short frame members 16, the filler block 20 having been withdrawn by reason of its attachment to cover 18. The shallow ribs 11 offer only a slight obstruction to sliding defectives from their support in the manner above described. Inspection being complete, the device is closed and set aside, preferably in a suitable rack designed to contain a number of such devices, to await the "check" sample inspection, which is accomplished by selecting an appropriate number of devices from those in storage and repeating the sequence of operation above described. The rack of primer holding devices is thereafter removed to the drying room and, after drying, to the shell priming machine, where each device is in turn opened in the manner illustrated in Fig. 2 and tilted to slide the lot of primers endwise off from the base 10 between the ribs 11 onto an inclined feed member associated with the shell priming machine.

While the device has been described as especially adapted to cartridge primers, it is obviously equally useful for other small articles, and the appended claims are to be so construed.

What is claimed is:

1. A device, for the reception, inspection, transportation and delivery of lots of small articles, comprising a frame having three continuous sides and a fourth side presenting a discontinuity, a base at one side of said frame having a pivotal movement with respect thereto, a cover at the opposite side of said frame having a pivotal movement with respect thereto, and a filler block hinged to said cover and adapted to complete said frame when said cover is in closed position.

2. A device, for the reception, inspection, transportation and delivery of lots of small articles, comprising a base provided with a pair of upstanding ribs located adjacent opposite margins thereof, a frame pivoted at one margin of said base and comprising three continuous sides and a fourth side presenting a gap, a cover pivoted upon another margin of said frame, and a filler block pivoted upon said cover in position to fill the gap in said frame when said cover is in closed position.

3. A device for the reception, inspection, transportation and delivery of lots of small articles comprising a frame having two ends, one continuous side and a second side comprising a discontinuity, said ends and sides being joined so as to define a substantially rectangular unicellular aperture for retaining said articles, said articles being removable therefrom through the discontinuity of said second side; a base for said frame for supporting articles therein; means to fasten

said base to one end of said frame for pivotal movement with respect thereto; a cover for said frame for holding articles on said base; and means to fasten said cover to the continuous side of said frame for pivotal movement with respect thereto.

4. A device for the reception, inspection, transportation and delivery of lots of small articles comprising a frame having two ends, one continuous side and a second side comprising a discontinuity, said ends and sides being joined so as to define a substantially rectangular unicellular aperture for retaining said articles, said articles being removable therefrom through the discontinuity of said second side; a base for said frame for supporting articles therein, said base comprising an imperforate substantially rectangular member, the ends and sides of which are substantially equal in length to the ends and sides of said frame; means to fasten one end of said base to a corresponding end of said frame for pivotal movement with respect thereto; a cover for said frame for holding articles on said base, said cover comprising an imperforate substantially rectangular member, the ends and sides of which are substantially equal in length to the ends and sides of said frame; and means to fasten one side of said cover to the continuous side of said frame for pivotal movement with respect thereto.

5. A device for the reception, inspection, transportation and delivery of lots of small articles comprising a frame having two ends, one continuous side and a second side comprising a discontinuity, said ends and sides being joined so as to define a substantially rectangular unicellular aperture for retaining said articles, said articles being removable therefrom through the discontinuity of said second side; a base for said frame for supporting articles therein, said base comprising an imperforate substantially rectangular member, the ends and sides of which are substantially equal in length to the ends and sides of said frame; means to fasten one end of said base to a corresponding end of said frame, said fastening means being constructed and arranged to enable said base to swing over onto one face of said frame; a cover for said frame for holding articles on said base, said cover comprising an imperforate substantially rectangular member, the ends and sides of which are substantially equal in length to the ends and sides of said frame; and means to fasten one side of said cover to the continuous side of said frame, said fastening means being constructed and arranged to enable said cover to swing over onto the opposite face of said frame.

6. A primer tray comprising a flat, substantially rigid frame surrounding and defining a central aperture adapted to loosely receive a primer die-plate, a gap interrupting one side of said frame to accommodate the die-plate handle, a flat, substantially rigid cover member movably related with said frame to close over and into marginal alignment with one face of said frame, a tab hinged to a margin of said cover to swing between coplanar extension outwardly from said cover margin and overlying engagement against the inner face of said cover margin in position to fill the gap in the interrupted frame side when said cover is closed, and a second flat, substantially rigid cover member movably related with said frame to close over and in marginal alignment with the other frame face.

PAUL J. NIEMACK.
